UNITED STATES PATENT OFFICE.

HARRY JACOBS AND HANNAH JACOBS, OF NEW YORK, N. Y.

HAIR-WAVING COMB.

1,360,643.

Specification of Letters Patent. Patented Nov. 30, 1920.

Application filed December 26, 1919. Serial No. 347,420.

To all whom it may concern:

Be it known that we, HARRY JACOBS and HANNAH JACOBS, citizens of the United States, and residents of New York, in the 5 county of Kings and State of New York, have invented certain new and useful Improvements in Hair-Waving Combs, of which the following is a specification.

This invention relates to improvements in 10 hair waving combs and consists of a series of arcuate combs suitably connected so that in use, alternate combs will move alternately in opposite directions to wave the hair when the said combs are brought together.

15 The object of this invention is to provide a device which, by its use, furnishes a simple means for readily waving the hair without the use of heat.

This object is attained by means of the 20 device shown in the accompanying drawing in which—

Figure 1 is a view, in plan, of the device when the parts are drawn together, showing the hair of the head in engagement therein, 25 and the form of wave made by the device; Fig. 2 is an extended view of same, and

Fig. 3 is an end view of the device as shown in Fig. 1.

Referring in detail to the parts, 1 designates a series of arcuate combs attached by 30 means of sliding members each consisting of the sections 3 and 4 having slots 5 and 6 formed therein which slots engage pins 7 upon one of the combs.

35 A second series of arcuate combs 8 are alternately arranged between the aforementioned combs and are connected by means of sliding members 9 and 10 having slots 11 and 12 which engage pins 13 secured upon 40 one of the combs.

The two series of combs are linked by

means of the bars 14 pivotally attached thereto.

In practice, the combs are drawn apart as indicated in Fig. 2, and placed upon the 45 head so that the teeth engage the hair which has previously been moistened.

The combs are then drawn together and assume the position shown in Fig. 1, drawing the hair in alternate directions forming 50 waves as indicated. The hair is allowed to dry whereupon the device is removed, leaving a wave which is commonly called "marcelle."

In the drawing, two series of combs each 55 having three combs are shown, but it is obvious that any number of combs may be employed.

Various modifications may therefore be embodied without departing from the spirit 60 of the invention which is not limited to the particular construction shown.

Having thus described the invention, it is claimed:

1. In a hair waving device, two series of 65 combs, the combs of each series being slidably attached to one another, pivotal connecting means between the two sets of combs to permit lateral movement thereof and means attached to each series of combs to 70 keep the combs of each series in alinement.

2. In a hair waving device, two series of arcuate combs, the combs of each series being slidably attached to one another, pivotal connecting means between the two sets of 75 combs to permit lateral movement thereof.

Signed at New York, in the county of Kings and State of New York, this 20th day of December, A. D. 1919.

HARRY JACOBS.
HANNAH JACOBS.
